UNITED STATES PATENT OFFICE.

GEORGE L. PIERCE, OF BROOKLYN, NEW YORK.

DESIGN FOR A PRESSER-FOOT FOR LEATHER-SEWING MACHINES.

SPECIFICATION forming part of Design No. 34,085, dated February 12, 1901.

Application filed January 21, 1901. Serial No. 44,217. Term of patent 14 years.

To all whom it may concern:

Be it known that I, GEORGE L. PIERCE, a citizen of the United States, residing in the city of New York, borough of Brooklyn, county of Kings, and State of New York, have invented and produced a new and original Design for a Presser-Foot for Leather-Sewing Machines, of which the following is a specification, reference being had to the drawings forming a part thereof.

In said drawings, Figure 1 represents a side elevation of a presser-foot for leather-sewing machines embodying the design. Fig. 2 represents a top or plan view of said presser-foot. Fig. 3 represents a front or edge view thereof.

As shown in the drawings, the essential feature of the design consists in providing a presser-foot *a* for leather-sewing machines with a lateral bearing-face *b*, formed by a

shoulder or enlargement *c*, and with a toe or biting edge *d*. The shoulder or enlargement *c* is beveled at an angle to the plane of the presser-foot to form said bearing-face. The presser-foot is also beveled to form the toe, and, as shown, the plane of said bevel forms an acute angle with the plane of the bearing-face.

What I claim as my invention, and desire to secure by Letters Patent, is—

The design for a presser-foot for leather-sewing machines herein described and shown.

In testimony whereof I sign this application, in the presence of two witnesses, this 17th day of January, 1901.

GEORGE L. PIERCE.
